UNITED STATES PATENT OFFICE.

WILLIAM C. KIRK, SR., OF CHATTANOOGA, TENNESSEE.

JACK.

1,418,654.

Specification of Letters Patent. Patented June 6, 1922.

Application filed March 21, 1921. Serial No. 454,048.

To all whom it may concern:

Be it known that I, WILLIAM C. KIRK, Sr., a citizen of the United States, residing at Chattanooga, in the county of Hamilton 5 and State of Tennessee, have invented certain new and useful Improvements in Jacks, of which the following is a specification.

This invention relates to improvements in jacks, and the particular adaptation which 10 has been selected for the purposes of illustration is a hand jack such as is in common use for elevating one end of an automobile in changing tires.

In jacks of this type it has been common 15 to employ mechanism requiring the use of a socket and handle, which is designed to be lifted and depressed under the control of a ratchet and pawl to raise the lifting element or rack bar, and to change the position 20 of certain of the parts and repeat the operation to accomplish the descent of the lifting element of rack bar. By this invention it is only necessary to use the ordinary tire tool to produce a rotary motion which 25 accomplishes the raising of the lifting element, while a reverse rotary movement will accomplish the descent.

The invention has for its object the production of a jack, which will be easy of 30 operation and efficient in use. Another object is the production of a jack in which the raising force is applied through the medium of a friction clutch, the frictional pressure between the clutch members being proportional 35 to the weight of the load. It has for a further object the production of a jack incorporating such a frictional clutch, which avoids any thrust action between the parts.

Other objects and advantages of the invention will hereinafter appear in the following description and the novel features thereof will be particularly pointed out in the appended claims.

In the drawings, in which like parts are 45 represented by like reference characters,

Figure 1 is a side elevation of the jack with cover plate removed,

Figure 2 is a section upon the line 2—2 of Figure 1,

50 Figures 3 and 4 are enlarged detailed views of the swivel head and pivoted foot of the jack, respectively, these views being sections taken upon the line 3—4 of Figure 1, and

Figure 5 is a like view taken at a right angle to Figure 4.

The numeral 10 represents the casing of the jack, which at the upper portion is enlarged into a gear casing 11. In this gear casing there is journaled the power shaft 12 and the countershaft 13. To the shaft 13 is keyed or otherwise secured a rack pinion and the large transmission pinion 15. The rack bar or lifting element is designated by the numeral 16 and travels in the casing 10 under the influence of the rack pinion 14.

Upon the shaft 12 at one end there is keyed the small transmission pinion 17 and at the opposite end abutting shoulder 22 there is splined the disk 18 of the friction clutch. 70 Slidably mounted and freely rotatable upon said shaft 12 is a cup element 19 of the friction clutch, cooperating with the disk of said clutch, and between these two clutch elements there is placed a friction washer 20 75 of any suitable material, leather having been selected for the purpose of illustration.

The shaft 12 is provided with a screw threaded end 23 projecting beyond the gear casing, upon which is mounted the force nut 24, by means of which the clutch members 18 and 19 are brought into frictional engagement, or released from said engagement. In order to prevent the force nut from being unscrewed from the shaft end 23, there is provided a locking disk 25 at the extremity of said shaft, which is held in place by the machine screw 26.

It will be noted that the cupped clutch member 19 is provided upon its periphery 90 with ratchet teeth 27, with which engage a pair of staggered pawls 28 and 29 supported by the gear case by means of the pin 30 and held in contact with the ratchet periphery of the clutch member by means of the 95 spring 31.

The gear casing 11 is open at both sides for the purpose of assembling the several parts therein, and the cover plates 32 and 33 are provided to protect the parts from the 100 dust, screws 34 being shown as the means for securing said plates to the casing. It is obvious that the gear case has been so formed as to conveniently accommodate the several parts and protect them in use.

At its upper end the rack bar 16 is provided with a swivel head 35 which is curved throughout its length to more efficiently en-

gage the portion of the automobile axle or axle casing. This head is secured to the rack bar by means of the rivet extension to the said bar. The lower end of the casing 10 5 is pivotally mounted upon the foot member, which is generally designated by the numeral 36 and which comprises the base 37, the lugs 38 and 39 provided with suitable openings to receive the bolt 40 passing through the sides of the casing or column 10 and through the lugs, and held in such position by means of the nuts 42 and 43. Suitable locking washers 44 and 45 are provided if found necessary. This construction of 15 foot member is desirable in order to obtain an even and secure footing for the jack upon uneven ground. At its lower end the rack is provided with a notch 41 which straddles the bolt 40. The teeth of the rack are not 20 extended to the bottom thereon, and the untoothed portion with the teeth on the pinion 14 constitutes a means to prevent accidental withdrawal of the rack from the casing. The lower end of the casing or column rests upon 25 the base 37 and is curved to permit of pivoting thereof within certain limits without destroying its contact with the base, it being understood that the relative size of bolt 40 and its receiving apertures will permit this 30 result, or provision may be made for a curved seat 46, as shown on the drawing.

It will be noted that the pivoted foot member, the swivel head and the rotative application of power combine to produce a jack 35 35 which is capable of use in any position made necessary by unevenness of ground or other causes.

The operation of the device may be readily understood from the foregoing description. The jack is placed under the axle or 40 axle casing of an automobile and the ordinary tire tool is placed upon the nut 24, which is then turned in a clockwise direction, bringing the nut into contact with the 45 cupped clutch member 19 and upon continued movement of the nut the cupped clutch member is brought into firm frictional contact with the disk clutch member 18 keyed to the shaft 12 and abutting shoulder 22. This avoids in the tightening of the clutch any thrust action between the 50 clutch members and parts of the casing and determines the amount of frictional pressure between the clutch members 18 and 19. When these members are in sufficiently firm 55 contact, continued turning movement of the nut will cause the shaft 12 to turn with the clutch members, when motion will be transmitted through the small gear 17 to the 60 large gear 15 and rack pinion 14, causing the rack bar 16 to be elevated. Since the frictional pressure between the clutch members is sufficient to cause the turning of the shaft 12, it will be appreciated that the 65 turning motion of the tire tool may be ar-

rested at any point, as the frictional contact will be sufficient to hold the load, it being understood that the cupped clutch member will be held by the pawls 28 and 29 cooperating with the toothed periphery. 70

To release the jack, it is only necessary to apply the tire tool to the nut 24 and turn the same slightly in a counterclockwise direction, when the frictional contact between the clutch members 18 and 19 will be relieved just enough to cause the weight of the load to transmit a reverse motion through the several gears to the shaft 12, which will tend to draw the nut back to re-establish the frictional contact between the 80 clutch members. It will thus be seen that the descent of the load will be easily accomplished and will be ever under the control of the user of the jack, and that the speed of descent can be either fast or slow as the 85 operator wills.

It will be observed that by this construction there is produced an efficient jack, which can be used for both raising and lowering the load without resetting of parts, 90 that there is no thrust between the parts, and that it requires for its operation no special handle, other than the ordinary tire tool, which is carried by all automobiles. 95

While I have shown and described one form of my invention, it will be understood that this form is for the purpose of illustration only, and that the invention is susceptible of many embodiments without departing from the spirit thereof as defined by the 100 appended claims.

What is claimed is:

1. In a jack comprising a supporting casing, a lifting element mounted for vertical movement within said casing, a power shaft and means for transmitting motion from said power shaft to said lifting element, a friction clutch upon said power shaft comprising fixed and movable members, and means for moving said movable member into frictional engagement with said fixed member, in application of power to the jack. 105 110

2. In a jack comprising a supporting casing, a lifting element mounted for vertical movement within said casing, a power shaft and means for transmitting motion from said power shaft to said lifting element, a friction clutch upon said power shaft comprising fixed and movable members, and means for controlling the frictional engagement of said clutch members and for rotating said power shaft. 115 120

3. In a jack comprising a supporting casing, a lifting element, a power shaft and means for transmitting motion from said power shaft to said lifting element, a friction clutch comprising a member fixed upon said power shaft, a movable member rotatably mounted upon said power shaft, 125 130

- means for forcing said members into frictional contact and for rotating said power shaft thereafter, and means for holding said movable member against retrograde rotative 5 movement, whereby the lifting element will be held in an elevated position until the frictional contact of the clutch members is released.
4. In a jack comprising a supporting 10 casing, a lifting element, a power shaft and means for transmitting motion from said power shaft to said lifting element, a clutch member rotating with said power shaft, a second clutch member rotatably mounted 15 upon said power shaft, means for forcing said clutch members into frictional contact, whereby upon rotation of said movable member the lifting element will be elevated, and means for holding said movable member 20 against retrograde rotative movement, whereby the lifting element will be held in its elevated position until the release of the clutch members is accomplished.
5. In a jack comprising a supporting 25 casing, a lifting element, a power shaft and means for transmitting motion from said power shaft to said lifting element, said power shaft having a screw threaded end, a clutch member fixed upon said power shaft, 30 and a second clutch member rotatably mounted upon said shaft, and means mounted upon said screw threaded end for causing the clutch members to be engaged and the power shaft to be rotated.
- 35 6. In a jack comprising a supporting casing, a lifting element, a power shaft and means for transmitting motion from said power shaft to said lifting element, said power shaft having a screw threaded end,
- fixed and movable clutch members upon said power shaft, an interiorly threaded operator cooperating with said screw threaded end, whereby a rotation of said operator in one direction will cause the clutch members to be engaged and the shaft rotated to 40 elevate the lifting element while a rotation of said operator in the opposite direction will relieve the frictional engagement of the clutch members and permit a controlled descent of the lifting element. 50
7. In a jack comprising a supporting casing, a lifting element, a power shaft and means for transmitting motion from said power shaft to said lifting element, said power shaft having a screw threaded end, 55 fixed and movable clutch members mounted upon said power shaft, a nut upon said screw threaded end cooperating therewith to cause engagement of said clutch members, means for holding the movable clutch member against retrograde rotative movement, and means for maintaining the nut upon said power shaft. 60
8. In a lifting jack, an operating mechanism comprising a power shaft having a screw threaded end, a clutch member fixed upon said power shaft, a movable clutch member rotatably mounted upon said shaft, and an operator having a threaded bore for cooperation with said screw threaded 65 end, whereby a rotation of said operator relative to said shaft will cause the clutch members to engage and a further rotation of said operator will cause the power shaft to rotate. 70

In testimony whereof I affix my signature.

WILLIAM C. KIRK, Sr.
